AIR CONDITIONING

Edmund Altenkirch, Neuenhagen, near Berlin,
GermanyApplication September 30, 1937, Serial No. 166,466
In Germany October 2, 1938

15 Claims. (Cl. 62—89)

This invention relates to apparatus for maintaining refrigerated air at substantially uniform humidity. It is well known that the relative humidity of the air in refrigerator cabinets varies over a wide range. This variation is due primarily to the fact that the refrigerator operates intermittently in response to the load on the machine and the temperature condition in the space being cooled. In this type of refrigerator, when the evaporator is operating, the relative humidity is too low due to the low temperature of the evaporator, and when the evaporator is not functioning the relative humidity rises. This variation in moisture content in the air is undesirable.

Attempts have been made to reduce these variations in relative humidity by starting and stopping the refrigerator frequently, and also by providing cold storage devices. The first of these remedies is not applicable if the electric current is interrupted for several hours, and the latter remedy is not practical because it is undesirable and impractical to provide refrigerators with cold accumulators. Attempts have also been made to increase the relative humidity by evaporating water into the air.

One of the objects of this invention is to provide means whereby the relative humidity of cooled chambers may be maintained substantially constant in a manner which is independent of the frequency of operation of the cooling means for the chamber or the length of the periods of operation of the cooling means. More specifically, it is an object of my invention to utilize hygroscopic material in such relationship to the cooling means for a chamber as to absorb moisture from the air whenever the relative humidity tends to rise and to liberate moisture whenever the relative humidity of the air tends to fall.

Several kinds of hygroscopic materials, such as silica gel, "fuller's earth" and like substances, may be employed to absorb the vapor from the cooled air to be delivered to the space being cooled. The hygroscopic material is likely to pick up food odors from the air and become unsuitable for further use until reconditioned. It is accordingly of advantage to provide means for easily exchanging hygroscopic elements in the refrigerator from time to time as may be necessary. If a plurality of single elements of hygroscopic material are used, they may be replaced one by one in rotation over a period of time. There are therefore a number of fairly fresh elements in the refrigerator as well as some which are nearly ready to be replaced.

The exposed surface of the hygroscopic material should be large in proportion to its weight, and the material should be so arranged that it offers only small resistance to the circulation of the box air thereover. Preferably the material

should be so arranged that at least part of it is in the stream of the air close to the evaporator, but protected from water dripping therefrom.

According to my invention, when the refrigerator is operating, the air first passes over the evaporator and a portion of this air comes into direct contact with the cold surface thereof. A considerable amount of water is likely to condense as this air contacts the cold surface of the evaporator thus leaving this air quite dry. This relatively dry air mixes with the air which does not directly contact the cold evaporator surface and then circulates about and contacts moist hygroscopic material and absorbs water from the latter prior to circulating into the room being cooled. This comes about by reason of the fact that the mixture of air flowing from the evaporator to the hygroscopic material has a higher temperature than that which directly contacted the cold surface of the evaporator and its relative humidity is therefore lowered due to the moisture condensed out of that portion which directly contacted the cold evaporator surface. This circulation of air about the hygroscopic material absorbs the moisture from the latter and dries it to a considerable extent so that when the refrigerator is not operating the hygroscopic material is in condition to pick up moisture from the air circulating thereabout. In other words, when the refrigerator is operating, the hygroscopic material gives up moisture to the air which results in a further cooling of the air stream; and when the refrigerator is not operating the relatively dry hygroscopic material absorbs moisture from the air as soon as the relative humidity rises, and this absorption results in a slight heating of the air.

This invention is primarily applicable to refrigerators in which the period when the refrigerator is operating is short relative to the period in which the refrigerator is not operating or to those in which both periods are comparatively long such as is used for large storage chambers for meats and other bulky products which must be maintained in a comparatively moist condition. In such machines, when the refrigerator is not in operation the surface of the evaporator will become appreciably warmer than during the period when the refrigerator is operating. The frost formed on the evaporator during operating periods will thus slowly evaporate into the air stream and this evaporated moisture will be absorbed in the hygroscopic material as described and replenish the moisture supply for addition to the air stream during the period the refrigerator is operating, and thus maintain the humidity of the circulating air at a more even value.

If desired, the hygroscopic material may be placed in heat transfer relation with a cold-storing device, which stores the cooling effect

caused by the extraction of water from the hygroscopic material, and when the latter absorbs water the heat of absorption liberated is absorbed by the cold-storing device. The type of cold-storing device proposed by me is easily installed in a refrigerator and renewal is not necessary. Since it is desirable to replace the hygroscopic material, and also to maintain portions thereof in heat transfer relation to the cold-storer or accumulator, I have provided a simple and easily operated means for detachably securing bodies of hygroscopic material to the accumulator.

Other objects and advantages will become apparent in the following description and drawing in which like numerals are employed to designate like parts throughout the several views.

Fig. 1 is a broken elevation of the refrigerator and humidity control apparatus;

Fig. 2 is a side elevation partly in section of the apparatus shown in Fig. 1;

Fig. 3 is a longitudinal section of a humidity control element;

Fig. 4 is a section on the lines 4—4 of Fig. 3;

Fig. 5 is a view partly in elevation and section of another form of humidity control device;

Fig. 6 is a section on the lines 6—6 of Fig. 5;

Fig. 7 is a section of another form of humidity control element embracing a cold-storing device, and

Fig. 8 is a section on the lines 8—8 of Fig. 7.

Figures 1 and 2 show a preferred arrangement of cold-storing elements 10 and humidity control elements 11 with respect to an evaporator 12 of a refrigerator generally indicated by numeral 13. It will be observed that these elements are disposed at one end of a room 14, not completely shown, and which is to be cooled and uniformly humidified. In order to form a definite path for circulating the air in the direction indicated by the arrows in Fig. 2, panels 20, 21 and 22 may be positioned near rear wall 23 to provide therebetween a conduit or passage 24. The top panel 20 terminates short of the top wall 25 to provide an inlet opening 26 above the evaporator 12 to passage 24. Spaced from the rear panel 22 is a lower front panel 27 forming a passage 28 therebetween having an outlet 29 formed between the front panels 20 and 27. These panels may be secured to the side walls of the refrigerator by any suitable means as by screws 30. As shown, the evaporator comprises coiled pipe 19 having an inlet 31 and an outlet 32 and is provided with heat absorbing fins 33.

The accumulator elements 10 are shown in detail in Figs. 7 and 8 and comprise an elongated cylindrical metal casing 35 closed at both ends and filled partly with a cold-storing liquid 36 having a fairly large heat of fusion at the temperature desired in the room to be cooled. At temperatures below the melting point of ice, aqueous solutions of inorganic substances, for example common salt, may be used. Surrounding substantially the longitudinal length of the casing 35 is a hygroscopic material 37, composed for example, of a corrugated paper container 38 having its cavities adjacent casing 35 filled with fuller's earth, or the like. The hygroscopic element 37 does not completely envelop the casing 35, but has its longitudinal edges separated as indicated at 39 in Fig. 8, so that it may easily be removed from the casing 35 whenever desired. The cold-storing effect of the liquid 36 can be adjusted to any desired relation with respect to the absorption effect of the hygroscopic material 37 by altering the size of the casing 35 with re-

spect to the quantity of the hygroscopic material 37.

The cold-storing elements 10 are supported in the air passage 24 by means of spaced brackets 5 mounted on the horizontal panel 21 and having upwardly extending bifurcated arms 41 to which are attached arcuate spring clamps 42 for detachably receiving the cold-storing elements 10. A drip pan 45 is supported by the upper ends of the bifurcated arms 41, and functions to collect the liquids that drip from the evaporator 12 to prevent the liquid from contacting the hygroscopic materials.

As shown in Figs. 1 and 2, the humidity control elements 11 are suspended from hooks 50 carried by a plurality of spaced panels 51 supported by the front and rear panels 27 and 22 respectively. This arrangement of the supporting panels 51 provides a plurality of separate air conduits 61 for circulating the air about the elements 11.

One of the humidity control elements 11 is shown in detail in Figs. 3 and 4 and comprises an elongated, substantially elliptical body 53 having a covering 54 of material pervious to water vapor, such as paper, and contains a hygroscopic material 55, for example sawdust. The ends of the covering 54 are glued together to form tabs 56 one of which is provided with an aperture 57 for suspending the element 11 from one of the hooks 50.

Another form of humidity control element 60 is shown in Figs. 5 and 6 and comprises an elongated cylindrical body having a wire screen cover 62 containing a hygroscopic material such as silica gel 63. One end 64 of the covering is closed and the other end is provided with a threaded coupling 65 for the removable connection of a cap 66 whereby the wire screen or silica gel can be replaced. An opening 67 is provided in the cap 66 for suspending the humidity control element from one of the hooks 50.

In operation, assuming that the evaporator 12 is operating, the air passes from room 14 through the inlet 26 and contacts the cold surface of the evaporator 12. The evaporator not only cools the air, but removes a considerable amount of moisture from the air which comes into contact with its cold surfaces leaving this air quite dry. The air which contacted the cold surfaces of the evaporator mixes with other air flowing adjacent to the evaporator, then passes downwardly into the conduit 24 and contacts the combined cold storage and hygroscopic elements 10. This air mixture has a lower relative humidity due to the fact that it is at a higher temperature than the part thereof which contacted the cold surfaces of the evaporator and some of the moisture in that part was condensed out. Under these conditions elements 10 have a temperature higher than the cooled air, and therefore the hygroscopic material 37 gives up water vapor to the air increasing its relative humidity. The heat required to evaporate the moisture is derived from the cold-storing elements, and consequently these elements are cooled as the air is humidified. Some heat may also be taken from the air. The hygroscopic material 37 being in contact with the cold-storing cylinder 35 will become quite dry because its temperature remains higher than the temperature of the cooled air due to the heating effect of the cold-storing cylinder 35. The air then continues to flow downwardly in conduit 24 and absorbs a small amount of heat by contacting the adjacent walls of the box, and then passes

upwardly in the conduit 28 where it is further humidified and cooled by contacting and absorbing water vapor from the hygroscopic material of the humidifying elements 11, with consequent drying of the hygroscopic material.

The air passing through the outlet 29 enters the room 14 with a higher relative humidity than it had upon entering the passage 24 below the evaporator, and the hygroscopic materials on the elements 10 and 11 are dried by this circulation and are thus prepared to absorb water vapor from the air when the evaporator is not operating.

When the operation of the evaporator is discontinued, the air continues to circulate in the same direction as previously because the evaporator and the cold storing elements are located at the top of the confined air passage. Since the temperature of the evaporator soon begins to rise, the air will no longer be dried by condensation. If the humidity tends to rise due partly to the dehydration of food or other materials being stored in the refrigerator and partly due to the gradual evaporation of frost or condensate from the evaporator due to its rise in temperature, the dry hygroscopic material in the air passage will absorb this moisture. The heat of absorption produced at elements 37 is taken up by the cold-storing elements 10, while that produced at elements 11 is given up to the air. Since the elements 11 are in the path of upwardly flowing air the heat generated therein by the absorption of moisture will augment the air circulation. It will be appreciated that the cold storing elements not only aid in circulating the air, but these are also very effective in reducing any excess humidity because their temperature remains lower than the box temperature.

If desired, the cold-storing devices 10 and humidity control elements 11 may be arranged in a different manner. For example, they may be disposed in any part of the room 14 or in air ducts leading to other rooms to be cooled. The hygroscopic elements 11 may be laminated or may consist of corrugated paper discs which may be filled with "fuller's earth." The hygroscopic material may also be used in a rack employed for supporting the material to be refrigerated. Solid hygroscopic material of the organic type, may also be used and is well adapted for easy replacement.

From the foregoing description of my invention, it will be seen that I have provided a simple, inexpensive means for controlling the humidity of refrigerated spaces which is automatic in operation and yet requires no controls or regulating means. While I have described a preferred way of practicing the invention it will be understood that the principle thereof may be carried out in various ways and by apparatus very different from that herein described.

I claim:

1. That method of conditioning air which comprises passing air from a space being conditioned into heat exchange relation with a cooling medium to cool the same, conducting the cooled air over moist hygroscopic material in heat exchange relation with a body having a high heat capacity and an initial temperature above that of said cooled air, whereby said cooled air is humidified by the evaporation of moisture thereinto from said material, and the heat of evaporation is supplied by said body of high heat capacity, and then returning the resulting cooled, humidified air to said space to condition the same.
2. In combination, a refrigerator chamber suitable to store food, means providing an air passageway having separate communication with both the top and bottom portions of said chamber, an evaporator of an intermittently operated refrigeration apparatus positioned to cool air in said passageway, and bodies of moist hygroscopic material in said passageway below said evaporator, said air circulating through said chamber and passageway by thermosyphonic action, coming first in contact with said evaporator and then with said hygroscopic material, whereby the air is chilled and then humidified by the evaporation of moisture from said hygroscopic material.
3. The combination set forth in the preceding claim characterized by the fact that at least some of said hygroscopic material is in heat exchange relation with bodies of high heat capacity whereby the heat of evaporation is supplied by said bodies thereby resulting in the chilling of said bodies so as to maintain the temperature of the refrigerator chamber during inactive periods of said apparatus.
4. A combined heat accumulator and humidity control device for refrigerated chambers comprising a self-contained heat storage element complete within itself, and means, including hygroscopic material mounted in heat exchange relation with said element, for absorbing moisture from ambient air when the humidity rises above a desired value, and for liberating moisture to the air when the humidity falls below a desired value, said heat storage element being operable to absorb heat of absorption during the absorption period, and to supply heat of evaporation during the period when the air is being humidified.
5. A combined heat accumulator and humidity control device for refrigerated chambers comprising a heat storage element complete within itself adapted to be supported in a refrigerated air passageway, and casing means readily pervious to moisture and containing hygroscopic material and adapted to be removably supported with said material in heat exchange relation with said element, said device being operable to remove moisture from ambient air when the humidity is too high and to add moisture when the humidity is too low without appreciably affecting the temperature of the air as the result of absorption and evaporation of moisture.
6. The combination set forth in the preceding claim characterized by the fact that said casing is so constructed as to have a larger surface area than is required to retain the volume of hygroscopic material contained therein.
7. The combination set forth in claim 5 characterized by the fact that said heat storage element contains a liquid having a low fusion temperature.
8. The combination set forth in claim 5 characterized by the fact that said casing is sufficiently resilient to permit the same to be placed upon the heat storage element and to be frictionally held thereto.
9. The combination set forth in claim 5 characterized by the fact that said heat storage element is of cylindrical form, and said casing means is made of flexible, resilient material adapted to be inserted around said element so as to be retained in place thereon by reason of said resiliency.
10. The combination with means forming an air passageway for air being conditioned, of means for chilling said air below the dew point

when operating, and a combined heat storage and humidity control device on the air discharge side of said chilling means, said device including hygroscopic material in heat exchange relation with said heat storage element, said device functioning to humidify the chilled air when said chilling means is operating and to absorb excess moisture from the air when said means is not operating, to control the humidity of the air, said humidity control also being operable to absorb heat of absorption and to supply heat of evaporation whereby the temperature of the air is not materially affected by the operation of said humidity control.

11. In the art of conditioning a refrigerated space, in which air is circulated from the refrigerated space through a conditioning space and back to the refrigerated space, and in which a portion of the air being circulated through the conditioning space comes into contact with a cold surface whereby the air is cooled and dehydrated by condensation of moisture therein onto the cold surface, that improvement which consists in bringing the previously cooled and dehydrated air into heat exchange with comparatively warm air from the refrigerated space and with a body of high heat capacity conditioned to temper the previously cooled air and into contact with a body of hygroscopic material conditioned to give up moisture to the previously dehydrated air whereby the previously dehydrated air is humidified and the heat of evaporation of the moisture is supplied from the warm air in the refrigerated space and from the body of high heat capacity.

12. In a refrigerating apparatus including a refrigerated space, an evaporator, and means for providing for the continuous circulation of air through said refrigerated space and over said evaporator, said apparatus operating intermittently to evaporate refrigerant in said evaporator whereby the circulating air is intermittently cooled and dehumidified by contact with the cold evaporator during the period when refrigerant is being evaporated in the evaporator and the previously condensed moisture is re-evaporated into the circulating air during the period when no evaporation is taking place in the evaporator, that improvement which consists in placing a body of hygroscopic material in a position to contact the circulating air after having contacted said evaporator, whereby the hygroscopic material will absorb the moisture evaporated into the air during the period when no evaporation is taking place in the evaporator and will give up the absorbed moisture to the dehydrated air during the period when evaporation is taking place in the evaporator.

13. A refrigerating apparatus comprising, a refrigerated space, an evaporator positioned therein, means providing for the continuous circulation of air through said space and over said evaporator, said evaporator being operated intermittently to evaporate refrigerant therein, whereby air contacting the surface of the evaporator is cooled and dehumidified by condensation of moisture therein onto the cold surface of the evaporator during the period that refrigerant is evaporating in the evaporator and the condensed moisture is re-evaporated into the circulating air during the period when no refrigerant is evaporating in the evaporator, and a hygroscopic body positioned to be contacted by

the circulating air after it has come into contact with the evaporator whereby the hygroscopic body will absorb the moisture evaporated into the circulating air during the period when no refrigerant is evaporating in the evaporator and will give up moisture to the dehumidified air during the period when refrigerant is evaporating in the evaporator so that the air in the refrigerated space will be maintained substantially constant, said hygroscopic body including a casting pervious to moisture containing hygroscopic material.

14. In the art of controlling the temperature and humidity of a refrigerated space, in which air is continuously circulated from the refrigerated space through a conditioning space and back to the refrigerated space, in which a portion of the air being circulated through the conditioning space comes into contact with a cold surface during one period whereby the air is cooled and dehydrated by condensation of moisture therein onto the cold surface and the total moisture content of the circulating air is reduced, and in which the moisture condensed on the cold surface is re-evaporated into the circulating air during a second period, that improvement which consists in contacting the air circulating through the conditioning space during the first period with a hygroscopic material conditioned to give up moisture to the previously dehydrated air and in heat exchange with a body of high heat capacity conditioned to give up heat to the previously cooled air whereby the circulating air is humidified and tempered during the first period and in contacting the air circulating through the conditioning space during the second period with the previously dried hygroscopic material to absorb moisture evaporated into the air from the cold surface and into heat exchange with the previously cooled body of high heat capacity whereby the circulating air is dehumidified and the heat of absorption of the moisture is taken up by the body of high heat capacity during the second period.

15. In the art of controlling the humidity of a refrigerated space, in which air is continuously circulated from the refrigerated space through a conditioning space and back to the refrigerated space, in which a portion of the air being circulated through the conditioning space comes into contact with a cold surface during one period whereby the air is cooled and dehydrated by the condensation of moisture therein onto the cold surface and the total moisture content of the circulating air is reduced, and in which the moisture condensed on the cold surface during the first period is re-evaporated into the circulating air during a second period, that improvement which consists in contacting the air circulating through the conditioning space during the first period with a hygroscopic material conditioned to give up moisture to the previously dehydrated air and in contacting the air circulating through the conditioning space during the second period with the previously dried hygroscopic material to absorb moisture evaporated into the air from the cold surface whereby moisture is absorbed by the hygroscopic material when the humidity of the air tends to rise and is liberated therefrom when the humidity tends to fall.

EDMUND ALTENKIRCH.
